Brooklyn, N.Y., attys.

UNITED STATES PATENT OFFICE.

JOSEPH T. COVO, OF FALL RIVER, ASSIGNOR TO GEO. DRAPER & SONS,
OF HOPEDALE, MASSACHUSETTS.

SLEEVE-WHIRL SPINDLE.

SPECIFICATION forming part of Letters Patent No. 502,225, dated July 25, 1893.

Application filed April 10, 1893. Serial No. 469,675. (No model.)

To all whom it may concern:

Be it known that I, JOSEPH T. Covo, of Fall River, county of Bristol, State of Massachusetts, have invented an Improvement in 5
5 Sleeve-Whirl Spindles; of which the following description, in connection with the accompanying drawings, is a specification, like letters and figures on the drawings representing like parts.

10 In the use of ring spinning frames in spinning, it is customary to provide the bolster case with a hook or other contrivance to overlap the upper portion of the band-receiving portion of the whirl to thereby prevent the 15 lifting of the spindle from its bearings during the doffing operation. The use of hooks to overlap a portion of the whirl, as stated, is objectionable because the hooks act to catch lint, and they are in the way and frequently 20 interfere with the bands, and the operator is delayed much in keeping clean the exposed parts of the bolster-case.

In accordance with my invention I have done away with the usual hook referred to, 25 and instead I have provided the lower end of the whirl with a flange, preferably made of a soft metal which can be cut and bent to form a band, this flange secured to the whirl co-operating with a suitable pin or projection 30 extended horizontally from the bolster case, but located, however, within the chambered lower end of the whirl.

Figure 1, in elevation and partial section represents a spindle having a sleeve whirl 35 embodying my invention; and Figs. 2 and 3, represent the notched flange in two positions.

The rail A receives upon it the supporting case B held in place by the nut C, said case containing in practice the usual bolster and 40 step bearings for the foot of the spindle D having a sleeve whirl E. I have provided the supporting case externally with a pin or projection a, and I have provided the lower end of the whirl with a flange b composed 45 preferably of wrought or sheet metal and notched, as at 2, to form an upturned tongue 3, the flange being herein shown as attached to the chambered lower end of the whirl by suitable screws 5 which should pass through holes 50 6, (see Fig. 3,) in the flange. When this spindle

is to have its foot put into the bearing, the flange b will meet the projection a, and the whirl will be turned until the arrival of the slot 2 at the pin or projection a, and in this position the projection a will pass through the 55 slot 2 and enter the chambered front end of the whirl above the plate b, which chamber in the whirl is sufficiently large above the free end of the tongue 3 to let the spindle and whirl revolve without the tongue striking the projection a. When the bobbins are 60 being doffed, the flange, by striking the under side of the projection a will prevent the spindle being lifted from its bearings. Should it be desired to remove the spindle from its 65 bearings, the operator will first lift the spindle somewhat and will then rotate it in a direction opposite to its usual travel when spinning, until the end of the tongue 3 meets the pin a, and then the operator will further lift 70 the spindle, the slotted portion 2 of the flange permitting the spindle to be lifted completely from its usual bearings.

This invention is not limited to the exact shape of the projection a b, or to the exact 75 part of the supporting case or rigid part of the spinning-frame to which it may be connected, so long as the end of the projection is adapted to and may enter the chamber at the lower end of the whirl.

80 My invention constitutes an inside catch to prevent the sleeve whirl spindle against unduly rising during the doffing operation.

Having described my invention, what I claim as new, and desire to secure by Letters 85 Patent, is—

A sleeve whirl spindle having an attached slotted flange, and tongue located to partially cover said slot, combined with bearings for the spindle, and a pin or projection adapted 90 to enter the chambered lower end of the whirl and co-operate with the said flange, substantially as and for the purposes set forth.

In testimony whereof I have signed my name to this specification in the presence of 95 two subscribing witnesses.

JOSEPH T. COVO.
